UNITED STATES PATENT OFFICE.

RICHARD C. STEWART, JR., AND WALLACE A. STEWART, OF COVINGTON,
KENTUCKY.

WROUGHT-METAL JOIST-HANGER.

SPECIFICATION forming part of Letters Patent No. 625,427, dated May 23, 1899.

Application filed December 29, 1898. Serial No. 700,607. (No model.)

To all whom it may concern:

Be it known that we, RICHARD C. STEWART, Jr., and WALLACE A. STEWART, citizens of the United States, residing at Covington, in the county of Kenton and State of Kentucky, have invented certain new and useful Improvements in Wrought-Metal Joist-Hangers; and we do hereby declare the following to be a full, clear, and exact description of the invention, reference being had to the annexed drawings, which form a part of this specification.

This invention relates to those joist hangers or stirrups which are readily formed by first cutting a number of blanks from a metallic plate and then bending said blanks to the desired shape; and our improvement comprises such a hanger which combines, in an eminent degree, the threefold qualities of strength, cheapness, and simplicity of construction, the details of said device being hereinafter more fully described.

In the annexed drawings, Figure 1 is a plan showing a flat plate or sheet of metal so cut as to afford blanks for forming two kinds of hangers. Fig. 2 shows one of said blanks separated from said sheet. Fig. 3 shows the first step in the formation of a hanger from said blank. Fig. 4 shows the succeeding step in forming said device. Fig. 5 shows a right and left pair of these hangers joined together by a tie-plate. Fig. 6 shows another form of blank separated from the metallic sheet. Fig. 7 shows the first step in the formation of a hanger from said blank. Fig. 8 shows the succeeding step in forming said device. Fig. 9 shows a modification of this last form of hanger. Fig. 10 shows another form of blank separated from the metallic sheet. Fig. 11 shows a pair of hangers made from such a blank and joined together with a tie-plate. Fig. 12 shows an elaboration of this form of hanger. Fig. 13 shows the back of a transversely-ribbed plate or sheet so cut as to afford blanks of the same size and shape as those shown in Fig. 1. Fig. 14 shows a blank separated from said sheet. Fig. 14^a shows on an enlarged scale the front of the aforesaid blank. Figs. 14^b, 14^c, and 14^d show successive steps in the formation of a hanger

from said blank. Fig. 14^e is an enlarged plan of the blank shown in Fig. 14^a. Fig. 14^f is a similar plan of the blank shown in Fig. 14^b. Fig. 15 shows right and left hangers made from said blank and joined together by a tie-plate. Fig. 16 shows another ribbed blank separated from said sheet. Fig. 16^a is an enlarged plan of said blank. Fig. 17 shows a hanger made from this ribbed blank.

Referring now to Fig. 1, A represents a plate or sheet of metal so rolled to the proper length, width, and thickness as to enable any desired number of blanks to be cut therefrom without causing any appreciable waste of material. A blank B when separated from said sheet has the peculiar shape shown in Fig. 2, reference to which illustration renders it clear that said blank has one long straight edge C and parallel with it two shorter straight edges D E, of substantially similar length and joined by an inclined edge F. Consequently the blank is wider at bottom than at top, and this wider end has a longitudinal slit G cut in it, which slit is in line with the upper straight edge D. The blank having been cut to the above-described shape is formed into a hanger or stirrup in the following way: Its upper end is bent back at the dotted line 1, so as to form a horizontal bearing b to rest upon a wall or heading, while its lower end is bent forward at the dotted line 2, thereby affording a horizontal seat b' for supporting joists, &c. The portion F E of the blank is then bent forward at the dotted line 3 until it stands at a right angle with reference to the plate B. (See Fig. 3.) Consequently the portion E of the blank projects some distance below the seat b', but is subsequently bent laterally in under said seat and riveted thereto, as seen at e in Fig. 4, thereby affording a very cheap and secure hanger which will suffice for all ordinary building purposes, because the seat is composed of two thicknesses of metal, and each one has a right-angle bend in it. By simply making a reversed facsimile of said blank, as at B' C' D' E' F' G', right and left hand hangers or sections are afforded, and then by joining their seats together by a tie-plate H (shown in Fig. 5,) a stirrup can be afforded of any desired width. Such a stirrup can be used for

supporting a beam composed of a number of joists spiked together side by side; but the blank shown in Fig. 6 enables a wide hanger to be made without using a tie-plate, and consists, in fact, in making an equivalent of the two blanks B B' out of one piece of metal. Accordingly said blank I has at its lower or wider end a pair of parallel longitudinal slots $g' g''$ in line with the edges of its upper and narrower end. It also has side pieces or wings $E'' E'''$ and inclined or oblique edges $f' f''$. To form a hanger from this blank, its upper end is bent back horizontally, so as to afford a wall or beam flange i , while the lower end of said blank is bent forward horizontally, thereby producing the seat or joist-support i' . The portions $E'' f' E''' f''$ are then bent forward and stand at right angles to the plate I. (See Fig. 7.) The ends of the sides $E'' E'''$ are finally bent in under the seat i' and riveted thereto, thereby forming the complete hanger shown in Fig. 8. Fig. 9 shows an elaboration of this last form of the hanger, wherein the plate I has longitudinal corrugations or ribs I' and a wall-plate I'' , that add very materially to its strength without increasing the cost of manufacture.

Fig. 10 shows a blank that differs very little from the one illustrated in Fig. 2, the difference consisting in slightly widening the narrower end of said blank, as at J , so as to form a vertical flange on the hanger, as shown at j , Figs. 11 and 12. In Fig. 11 a pair of these right and left sections are joined together by a tie-plate H' .

Fig. 12 shows a hanger made from a blank of the same shape as that represented in Fig. 6, with the addition of the proper widening of the upper end of this latter blank to afford a pair of vertical flanges j . Again, Fig. 12 shows a stiffening-plate K applied to the back and bottom of the hanger, which plate is usually cut from the sheet A when the other blanks are formed.

In an elaboration of our invention shown in Fig. 13 the sheet or plate A' is so rolled as to have projecting from its back a number of parallel integral transverse ribs a' and is so divided and slotted as to afford blanks of the same size and shape as those represented in Figs. 2 and 6.

A counterpart of the more simple form of blank shown in Fig. 2 is represented at B'' in Figs. 14 and 14^a, and, remembering that this latter illustration shows the front, not the back, of said blank, the method of converting it into a hanger is as follows: The blank is first bent forward in the plane of the slit G and dotted line $3'$ until the rib a' , which was previously at the back of said blank, is brought around squarely in front of it, thereby causing the wing F' to project at a right angle from the body B'' of said blank. This bending operation is indicated by the arrow in Fig. 14^c, while the blank at this stage of manufacture is shown by Figs. 14^b and 14^c. The upper part of the blank is then bent

back, so as to afford a horizontal wall-bearing b'' , and as a matter of course a portion of the rib a' also becomes horizontal by this operation. The next step consists in bending the lower portion of the blank horizontally forward, thereby forming a joist-seat, as shown at b''' in Fig. 14^c. Finally the lower portion of the wing F' is bent laterally at a right angle and secured under said seat B''' , as shown in Fig. 14^d, a part of the rib a' being carried around with said wing. By making these blanks rights and lefts and then fastening them together by means of a tie-plate H'' (shown in Fig. 15) a hanger of any width of seat can be made.

A more complex form of blank, also cut from the plate A', is shown in Figs. 16 and 16^a and includes a central section or body I'' , a pair of integral parallel ribs $a' a'$, and two longitudinal slits $g'' g'''$, or, in other words, this blank is a facsimile of the one represented in Fig. 6 and is bent in the same manner as the blank shown in Fig. 14^a, the only difference being that said blank I'' has two wings $F'' F'''$, as shown in Fig. 16^a. When these wings are properly bent around, they project at right angles from the front of the hanger, as indicated by the dotted lines $f'' f'''$. By simply bending the lower portions of these wings horizontally toward each other and then uniting them with a tie-plate the complete hanger shown in Fig. 17 is produced.

Again, the blanks B and B' (shown in Fig. 1) are right and left counterparts of each other, so as to economize in cutting up the sheets or plate A; but a single blank will answer for these parts by simply bending them either forward or backward to form the wall-bearings and seats.

From the above description it is evident the hangers shown in Figs. 4, 8, 9, 15, and 17 have their seats or joist-bearings formed of two thicknesses of metal, while the devices represented in Figs. 5, 11, and 12 have seats made of three thicknesses of material, and as the plates A or A' can be as heavy as can be cut the hangers will support a very great weight before bending or breaking.

We claim as our invention—

1. As a new article of manufacture, a rolled-metal joist-hanger including a plate B, having at top a rearwardly-projecting bearing b , at bottom a forwardly-projecting seat b' , and, at one side, a flange F , provided at its lower end with a lateral bend E , secured under said seat b' ; thereby affording a double thickness of metal where a joist is supported by said hanger, all as herein described.

2. As a new article of manufacture, a wrought-metal joist-hanger including right and left sections, constructed as above described and having their seats united together by a tie-plate.

3. As a new article of manufacture, a wrought-metal joist-hanger blank I'' narrower at top than at bottom, and provided on its front with a pair of parallel integral ribs

a' a' longitudinal slots *g'' g'''*, being cut in the wider end of said blank and close up to the inner sides of said ribs.

4. A joist-hanger blank having one long, straight edge C, and, parallel therewith, two shorter, straight edges D, E, joined by an inclined edge F, the wider end of said blank being slotted longitudinally at G, which slit is in line with the edge D, all as herein described.

5. A joist-hanger blank having one long, straight edge, and, parallel therewith, two shorter, straight edges joined by an inclined

edge; an integral rib being formed on the back of said blank, and a longitudinal slit 15 being made in its wider end, which slit is parallel with and along one side of the lower portion of said rib, all as herein described.

In testimony whereof we affix our signatures in presence of two witnesses.

RICHARD C. STEWART, JR.
WALLACE A. STEWART.
